COFFEE MAKER

Maurice H. Graham and John N. Polivka, Minneapolis, Minn.; said Polivka assignor to said Graham, Maurice W. Graham, and Northwestern National Bank of Minneapolis, all of Hennepin County, Minn., executors of said Maurice H. Graham, deceased

Application February 9, 1954, Serial No. 28,932

Term of patent 14 years

(Cl. D44—26)

Fig. 1 is a side elevational view of a coffee maker, showing our new design;

Fig. 2 is a rear elevational view thereof;

Fig. 3 is a top plan view thereof; and

Fig. 4 is a bottom plan view thereof.

We claim:

The ornamental design for a coffee maker, as shown.
